CONTROL SYSTEM

Van Allen McGovern and Elmer R. Gruchow,
Waterloo, Wis.

Application June 6, 1941, Serial No. 396,878

8 Claims. (Cl. 274—1)

This invention relates to multiple unit control systems.

For purposes of illustration and explanation, the control system of the present invention will be shown and described as applied to two automatic selective phonographs of a well known type for the purpose of effecting reproduction of any recorded sound rendition available in either machine to the exclusion of the other, although other uses are contemplated.

Automatic selective phonographs are ordinarily equipped with electrically actuated means, commonly coin controlled, for automatically placing in playing position on the turn-table any particular sound record selected from a limited number of sound records contained in the machine, for automatically lifting the pick-up arm from the played record and for returning the same into playing position with respect to the newly placed selected record, for automatically driving the turn-table with the selected record thereon, and for broadcasting the sound produced thereby through an appropriate loud-speaker electrically connected thereto and ordinarily embodied therein. Such machines perform quite satisfactorily, but their use is limited by the limited number of sound records contained therein.

One object of the present invention is to provide an electrical system by which the sound reproduced from a selected record in any of a plurality of phonographs may be broadcast through the loud speaker of either or both machines in such manner as to effectually prevent sound reproduction from more than one machine at a time.

Another object is to provide a system for the purpose mentioned which will permit the record selecting and positioning mechanism as well as the pick-up arm positioning mechanism of one machine to perform their usual functions while the other machine is playing, so as to be in readiness for instant starting as soon as the other machine has discontinued playing.

Another object is to provide an electrical system by which either of two electrically operated units may be set in operation, selectively, to the exclusion of the other.

Other more specific objects and advantages will appear, expressed or implied, from the following description of a control system constructed in accordance with the present invention.

In the accompanying drawing:

The single figure of the drawing is a diagrammatic illustration of a control system embody-

ing the present invention shown applied to two automatic selective phonographs of a well known type.

The system shown comprises two sets of conventional switches 5, 6, 7 and 8, and 5', 6', 7' and 8', each comprising a pair of coacting contacts individually mounted on spring leaves 9 and 10 anchored in a rail 11 of insulating material carried by an appropriate panel 12. The switches 5 and 6 of one set and 5' and 6' of the other set are normally closed, and the switches 7 and 8 of one set and 7' and 8' of the other set are normally open.

A suitable actuator, such as a bar 13 lengthwise reciprocable in appropriate guide blocks 14 on the panel 12, controls all of the switches of both sets. In this instance the bar 13 is shown provided with a plurality of fingers 15, each disposed to coact with the extended end 16 of the spring leaf 10 of one of the switches, so as to open the closed switches and close the open switches of one set, when the bar 13 is shifted in one direction from the neutral position shown, the switches of the other set remaining undisturbed and in the normal positions shown. When the bar 13 is shifted in the opposite direction from the neutral position, the closed switches of the other set are thereby opened and the open switches thereof closed, the switches of the first mentioned set assuming the normal positions shown.

In this instance, the bar 13 is actuated and controlled by two spaced electromagnets 17 and 17' mounted on the panel 12 and arranged to exert magnetic pulls in opposite directions on an armature 18 disposed therebetween. The armature 18 is carried by one end of a lever 19 mounted intermediate its ends upon a pivot pin 20, carried by the panel 12, and connected at its other end with the bar 13 through a pin-and-slot connection 21. A spring 22 yieldably retains the armature 18, lever 19, and bar 13 in the neutral position shown, but permits the same to shift in one direction or the other whenever one or the other of the electromagnets 17 or 17' is energized.

The energizing circuit of the electromagnet 17 includes a line 23, permanently connected to a terminal 24 on the panel 12, and a line 25, which is controlled by the switch 5, and which is connected through line 26 with a terminal 27. The terminal 24 is connected to one side 28 of an electric power line through a line 29 containing a switch 30, and the binding post 21 is permanently connected to the other side 31 of the power

line through a line 32, so that, if the switch 5 is closed, the electromagnet 17 is energized upon closing the switch 30. The electromagnet 17 is similarly connected to one side 28 of the power line through line 23', terminal 24', line 29', and switch 30', and similarly connected to the other side 31 of the power line through the line 25', switch 5', line 26', terminal 27', and line 32, so that, if the switch 5' is closed, the electromagnet 17' is energized upon closing the switch 30'.

The arrangement is such that, with the bar 13 in the neutral position shown, both switches 5 and 5' are closed and either electromagnet 17 or 17' may be energized by closing one or the other of the switches 30 or 30'; but neither can be energized while the other is energized because, if the electromagnet 17 be energized, it functions to shift the bar 13 toward the left to thereby open the switch 5' and thus prevent energization of electromagnet 17', and likewise, if electromagnet 17' be energized, it functions to shift the bar 13 toward the right to thereby open switch 5 and prevent energization of electromagnet 17.

The switches conventionally shown at 30 and 30' represent switches ordinarily used for controlling the circuits of the turn-table motors in well known types of automatic selective phonographs. One such phonograph is conventionally indicated at 33 and another at 33', the turn-table motor circuit of one being represented by the line 34 and 35 and that of the other by the lines 34' and 35'. One side 34 of the motor circuit is connectable to one side 28 of the power line through the switch 30, and the other side 35 of the motor circuit is connected to a terminal 36 which is connectable through the switch 6, a terminal 37, and the line 32 with the other side 31 of the power line, so that, if the switch 6 is closed, the turn-table motor of the phonograph 33 is energized by closing the switch 30. Likewise, the side 34' of the other motor circuit is connectable to one side 28 of the power line through the switch 30', and the other side 35' of that motor circuit is connectable to the other side 31 of the power line through a terminal 36', switch 6', and terminal 37', so that, if the switch 6' is closed, the turn-table motor of the phonograph 33' is energized by closing switch 30'.

The arrangement is such that, with the bar 13 in the neutral position shown, the turn-table motor of either phonograph 33 or 33' may be energized by closing one or the other of the switches 30 or 30'. However, the instant the switch 30, for instance, is closed to energize the table motor of phonograph 33, the closing of that switch energizes the electromagnet 17, causing the bar 13 to shift to the left and open the switch 6', thereby rendering it impossible to energize the table motor of the other phonograph even though its switch 30' be closed, and this condition prevails until the table motor of phonograph 33 has been de-energized by subsequent opening of the switch 30. Likewise, if the switch 30' be closed while the switch 30 is open, the table motor of phonograph 33' will be energized, and the electromagnet 17' will also be energized, causing the switch 6 to open and thus prevent operation of the table motor of the phonograph 33 even though the switch 30 thereof be closed. It is thus impossible for the table motor of either phonograph to function while the other is in operation.

It will be further noted that, although the system above described prevents operation of the table motor of one phonograph so long as the

other is operating, it may effect automatic starting of the table motor of the second phonograph the instant that the table motor of the other machine is de-energized. For instance, if the switch 5' 30' of the phonograph 33' be closed, during operation of the other phonograph 33, so that it is closed when the switch 30 opens to stop the phonograph 33, the opening of the switch 30 de-energizes the electromagnet 17, thereby permitting the bar 13 to return to neutral and causing the switch 6' to close and complete the circuit through the table motor of phonograph 33'.

It will of course be understood that the phonographs 33 and 33' are conventional coin controlled machines, each having the usual mechanism for automatically placing a selected sound record on the turn-table in response to application of an appropriate coin thereto, mechanism for automatically lifting the pick-up arm from a played record and returning the same into playing position with respect to the newly placed selected record, and mechanism for automatically closing the turn-table motor switch 30 or 30' and for automatically reopening that switch to stop the turn-table when the selected record has been played. Such a combination of mechanisms is old and well known in that type of machine and need not be described here. It will be noted however that when two such machines are connected by the electrical system above described, either 20 may be set into operation by application of an appropriate coin thereto, unless the other be already functioning; and should one machine be operating at the time that a coin is applied to the other machine, the record selecting and positioning mechanism of that other machine, as well as the pick-up arm actuating mechanism and the mechanism for closing the table motor switch will function automatically in the usual manner, 25 but the table motor will not function until the switch controlling the table motor of the first machine has opened to stop the first machine. In other words, if a coin be applied to a second machine while the first machine is operating, the 30 mechanism of the second machine will function automatically in the usual manner to properly position the selected record and the pick-up arm and to close its turn-table switch, so that it is in readiness to start functioning the instant that 35 the first machine stops functioning.

The loud speakers of the two phonographs 33 and 33' are conventionally indicated at 38 and 38'. In this instance, both loud speakers are shown connected in parallel to the tone arms of 40 both phonographs through appropriate audio circuits 39 and 39'. Also both loud speakers are shown connected in parallel between two sides 40 and 41 of a circuit through which they are automatically connected to the opposite sides 45 28 and 31 of the main power circuit whenever either of the switches 30 or 30' is closed. Appropriate switch controlled lines for this purpose 50 will now be described.

In the system shown, line 40 from one side of 55 the loud speakers 38 and 38' is connected through a terminal 42 and line 43 with one side of each of the two switches 7 and 7', the other side of switch 7 being connectable through line 23', terminal 24', and switch 30' to one side 60 28 of the power circuit, and the other side of switch 7 also being connectable through line 23, terminal 24, and switch 30 to the side 28 of the power circuit. The other line 41 from the other side of the loud speakers is connected through a 65 terminal 44 and line 45 with one side of both

switches 8 and 8', the other side of switch 8 being connected through line 26', terminal 27', and line 32 to one side 31 of the power circuit, and the other side of switch 8' also being connected through line 26, terminal 27, and line 32 to the side 31 of the power circuit.

The arrangement is such that whenever the switch 30 is closed to energize the table motor circuit of the phonograph 33 and to energize the electromagnet 17 so as to shift the bar 13 to the left, the switches 7 and 8 remain open and the switches 7' and 8' are thereby closed, switch 7 connecting one side 49 of both loud speakers 38 and 38' to one side 28 of the power circuit through the closed switch 30, and the switch 8' connecting the other side 41 of both loud speakers to the other side 31 of the power circuit through the line 32. Likewise, when the switch 30' is closed to energize the table motor of the other phonograph 33' and to energize the electromagnet 17', the bar 13 shifts to the right, permitting the switches 7' and 8' to assume open positions and causing the switches 7 and 8 to close, switch 7 connecting one side 40 of both loud speakers to one side 28 of the power circuit through the closed switch 30', and switch 8 connecting the other side 41 of both loud speakers to the other side 31 of the power circuit through the line 32. Both loud speakers 38 and 38' are thus automatically connected across the power circuit 28-31 whenever the table motor of either machine is set into operation, and both thus broadcast the sound reproduced from the operating sound record regardless of whether that record be in one or the other of the phonographs.

Under some conditions it is possible that one machine may play a succession of records to the exclusion of the other machine even though in the meantime a coin may have been placed in the other machine. That may happen if a succession of coins have been placed simultaneously in the first machine. This is objectionable not only because the first machine thus monopolizes the playing time, but also because of the time consumed between successive renditions by that machine, a substantial period of time being consumed during each record-changing operation. This objection is eliminated in the system shown by the provision of means for insuring that either machine to which a coin has been supplied may cut in and play its record as soon as the other machine has completed a record, even though that other machine may be set to play a succession of records. The machines may thus be caused to function alternately, the pick-up arm actuator and record changing mechanism of the one machine functioning during the playing period of the other machine and vice versa, so that there is no playing time lost during the record changing operation of either machine. Although this may be accomplished in various ways, a means which has proven satisfactory for the purpose will now be described.

In this instance a switch 46 is included in the line 29 constituting a part of the energizing circuit for the electromagnet 17, and a similar switch 46' is included in the line 29' constituting a part of the energizing circuit for the electromagnet 17'. Both switches 46 and 46' are biased toward closed position so that the circuits of the two electromagnets 17 and 17' are normally unaffected thereby. However, each switch 46 and 46' is so related with a moving part of one of the machines 33 or 33' as to be automatically momentarily opened during the record changing operation thereof. In the system shown, the

switch 46 is momentarily opened by the lifting movement of the pick-up arm 47 of machine 33, that being the first step in the record-changing operation of that machine, and switch 46' is similarly momentarily opened by the lifting movement of the pick-up arm 46' of the other machine 33'. For that purpose the pick-up arm 17-47 of each machine is provided with a rearwardly extending trip finger 48-48' which swings downwardly as the arm lifts, and sweeps over a cam 49-49' on the switch 46-46' to momentarily open the latter.

The effect of this arrangement may be described as follows. Let it be assumed that the machine 33' for instance has received a number of coins and is thus set to play a succession of records and that it is playing one of them. Of course under such conditions its switch 30' is closed, the electromagnet 17' is energized, and the switch bar 13 is in its right extreme position. Now let it be assumed that attempt be made to start the other machine 33 by placing a coin in it. As hereinabove pointed out, the placing of a coin in the machine 33 will not then affect the operation of machine 33', but the machine 33 will proceed to carry out its record-changing operation and its switch 30 will ultimately close. The position of the switch bar 13 and the consequent open condition of the switch 6 will prevent operation of the table motor of machine 33. This condition will maintain until the machine 33' has completed playing its record and ultimately proceeds to lift its pick-up arm to start a record-changing operation. When this occurs, the switch 46' opens momentarily, thereby de-energizing the electromagnet 17' and permitting the switch bar 13 to momentarily return to neutral position. The instant this occurs, switches 5 and 6 close, so that the electromagnet 17 is thereby energized and the table motor circuit of the machine 33 thereby closed. The machine 33 then starts playing immediately, the electromagnet 17 having actuated the switch bar 13 into its left extreme position to break the table motor circuit of machine 33' and to render the loud speakers responsive to the machine 33 in the manner earlier described.

It will of course be understood that if no attempt has been made to start the machine 33, so that its table motor switch 30 is open at the time that switch 46' has been momentarily opened by the lifting of the pick-up arm of machine 33', the machine 33' will continue to function just as though the switch 46' had not been opened, because the instant that the switch 46' recloses, the electromagnet 17' is re-energized and the switch bar 13 returned to its extreme right position.

Various changes may be made in the embodiment of the invention hereinabove specifically described without departing from or sacrificing the advantages of the invention as defined in the appended claims.

We claim:

1. The combination of two electric phonographs each having a turn-table motor circuit, and switch means responsive to energization of either of said circuits for breaking the other of said circuits to thereby prevent operation of the turn-table of either of said phonographs while the other is operating.

2. In a multiple unit control system the combination of two energizing circuits, separate electromagnets responsive to each of said circuits, means controlled by one of said electromagnets for breaking one of said circuits when the other

of said circuits is energized, means controlled by the other of said electromagnets for breaking the other of said circuits when the first of said circuits is energized, and means for rendering either of said electromagnets inactive when the other is energized.

3. In a multiple unit control system the combination of two sets of switches, an actuator therefor moveable in one direction to actuate one of said sets of switches and in the opposite direction to actuate the other of said sets of switches, means including two electromagnets selectively operable to actuate said actuator in one of said directions or the other, and connections through which said electromagnets are controlled by said switches to prevent energization of either of said electromagnets when the other is energized.

4. The combination of two electric phonographs each having a turn-table motor circuit, switch means responsive to energization of either of said circuits for breaking the other of said circuits to thereby prevent operation of the turn-table of either of said phonographs while the turn-table of the other is operating, and means controlled by moving parts of said phonographs for preventing repeat playing of either of said phonographs in the event that the other of said phonographs has been set to play.

5. The combination of two electric phonographs each having a turn-table motor circuit, switch means responsive to energization of either of said circuits for breaking the other of said circuits to thereby prevent operation of the turn-table of either of said phonographs while the turn-table of the other is operating, and means controlled by a moving part of each of said phonographs for momentarily modifying the effect of said switch means to thereby permit the turn-table motor of the other of said phonographs to function.

6. The combination of two electric phonographs each having record-changing mechanism and a turn-table motor circuit controlled thereby, switch means responsive to energization of either of said circuits for breaking the other of said circuits to thereby prevent operation of the turn-table of either while the turn-table of the other is operating, and means controlled by the record-changing mechanism of each phonograph for momentarily modifying the effect of said switch means.

7. The combination of two electric phonographs each having a pick-up arm and a turn-table motor circuit, control means responsive to energization of either of said circuits for breaking the other of said circuits to thereby prevent operation of the turn-table of either while the turn-table of the other is operating, and means controlled by the pick-up arm of each phonograph for modifying the effect of said control means so as to permit the turn-table of the other of said phonographs to operate when the turn-table of the operating phonograph has come to rest.

8. The combination of two electric phonographs each having a record-changing mechanism and a turn-table motor circuit controlled thereby, control means responsive to energization of either of said motor circuits for breaking the other motor circuit to thereby prevent operation of either turn-table while the other turn-table is operating, said control means including a normally closed switch momentarily opened by movement of the record-changing mechanism of each of said phonographs so as to permit the turn-table of said other phonograph to operate when the turn-table of the operating phonograph has come to rest.

VAN ALLEN McGOVERN.
ELMER R. GRUCHOW.
